(57) **CLAIM**

The ornamental design for a main body for specimen storage container as shown and described.

DESCRIPTION

FIG. 1 is a perspective view of a main body for specimen storage container, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a sectional view thereof taken along line 8-8 of FIG. 2; and,

FIG. 9 is another perspective view with an unclaimed cap. The broken lines shown in FIG. 9 illustrate environmental structure that form no part of the claimed design.

1 Claim, 8 Drawing Sheets
